Primary Examiner — Janice Hallmark*Assistant Examiner* — Emily Anna Saunders(74) Attorney, Agent, or Firm — Dunlap Bennett & Ludwig, PLLC; Anna L. Kinney(57) CLAIM

The ornamental design for a die frame, as shown and described.

DESCRIPTION

FIG. 1 is a perspective view of a die frame showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of the die frame that form no part of the claimed design.

1 Claim, 4 Drawing Sheets(56)
